GOLF TEE

Louis E. Redmon, Rte. 1, Roscommon, Mich. 48653

Filed Jan. 18, 1973, Ser. No. 324,646

Term of patent 14 years

Int. Cl. D21—02

U.S. Cl. D34—5 GT

FIG.1

FIG.2

FIG.3

FIG.4

FIG.5

FIG. 1 is a side elevational view of a golf tee incorporating the design;

FIG. 2 is an end elevational view thereof;

FIG. 3 is an opposite side elevational view thereof;

FIG. 4 is a top plan view thereof; and

FIG. 5 is an under plan view thereof.

I claim:

The ornamental design for a golf tee, as shown and described.
